Primary Examiner — Richard E Chilcot*(74) Attorney, Agent, or Firm* — SANCHELIMA & ASSOCIATES, P.A.; Christian Sanelima; Jesus Sanelima**(57) CLAIM**

The ornamental design for a van, as shown and described.

DESCRIPTION

FIG. 1 is a perspective view from the front and right side of a van showing my new design;

FIG. 2 is a perspective view from the front and left side thereof;

FIG. 3 is a perspective view from the rear and left side thereof;

FIG. 4 is a perspective view from the rear and right side thereof;

FIG. 5 is a rear view thereof;

FIG. 6 is a front view thereof;

FIG. 7 is a right side view thereof;

FIG. 8 is a left side view thereof;

FIG. 9 is a top view thereof;

FIG. 10 is an elevational rear interior view thereof;

FIG. 11 is an isometric right interior view thereof; and,

FIG. 12 is an isometric left interior view.

The present design relates to a van, including a passenger van, a minivan, a utility van, a toy van, a replica van, a medical assistance van, and a scale-model van.

No claim is made to the wheels shown in broken lines, they are shown for illustration purposes only.

1 Claim, 11 Drawing Sheets(56)
